(57) CLAIM

The ornamental design for a tool pouch, as shown and described.

DESCRIPTION

FIG. 1 is a perspective view of a tool pouch showing my new design;

FIG. 2 is a front elevational view thereof;

FIG. 3 is a rear elevational view thereof;

FIG. 4 is a left elevational view thereof;

FIG. 5 is a right elevational view thereof;

FIG. 6 is a top view thereof;

FIG. 7 is a bottom view thereof; and,

FIG. 8 is a perspective view from another direction of the tool pouch.

The broken line portion of the figure drawings is included to show unclaimed subject matter only and forms no part of the claimed design.
